CLAIM

The ornamental design for a connection box for TV receiver, as shown and described.

DESCRIPTION

FIG. 1 is a top perspective view of a connection box for TV receiver showing my new design;

FIG. 2 is the front elevation view thereof;

FIG. 3 is the rear elevation view thereof;

FIG. 4 is the left-side elevation view thereof;

FIG. 5 is the right-side elevation view thereof;

FIG. 6 is the top plan view thereof;

FIG. 7 is the bottom plan view thereof; and,

FIG. 8 is a top perspective view thereof, in use condition. The broken line in the figure drawings is included for the purpose of illustrating unclaimed environment and forms no part of the claimed design.

The shade lines in the figures show contour and not surface ornamentation.
